UNITED STATES PATENT OFFICE.

ARTHUR W. WELLINGTON, OF WATERBURY, CONNECTICUT, ASSIGNOR TO WATERBURY MANUFACTURING CO., OF WATERBURY, CONNECTICUT, A CORPORATION.

SHADE OR GLOBE HOLDER.

1,070,644.

Specification of Letters Patent. Patented Aug. 19, 1913.

Application filed May 12, 1913. Serial No. 767,087.

To all whom it may concern:

Be it known that I, ARTHUR W. WELLINGTON, a citizen of the United States, residing at Waterbury, in the county of New Haven and State of Connecticut, have invented a new and useful Improvement in Shade or Globe Holders; and I do hereby declare the following, when taken in connection with the accompanying drawings and the characters of reference marked thereon, to be a full, clear, and exact description of the same, and which said drawings constitute part of this application, and represent, in—

Figure 1 a side view of a shade or globe holder constructed in accordance with my invention. Fig. 2 a side view at right angles to Fig. 1. Fig. 3 an underside view of the same with the shade-gripping fingers in their locked or holding positions. Fig. 4 a similar view with the shade-gripping arms in the open position.

This invention relates to an improvement in shade or globe holders, and particularly to that class which comprise a cup-shaped socket or holder with a wire shade or globe gripping device.

The object of this invention is to provide a wire gripping device which will firmly grip the globe or shade when inserted and which will provide a free opening for the insertion of a shade or globe; and the invention consists in the construction hereinafter described and particularly recited in the claim.

In carrying out my invention, I employ a shell 2 of any approved design having a flange 3 corresponding in diameter to the shade or globe to be held. On opposite sides of the shell are short slots 4, 5, while midway between them are perforations 6, 7, and opposite the perforations are long slots 8, 9, the inner ends of which may intersect. Combined with the shell thus formed I employ two gripping arms 10, 11. The end 12 of one arm is turned outward through the perforation 6; is formed in line with slot 4 with a sharp U-shaped bend 13, and at its outer end which projects through the slot 9, with a finger-piece 14. Between the bend

13 and finger-piece 14 is a bend or knee 50 which has a bearing against the inner face of the shell forming a fulcrum, so to speak, on which the gripping-arm or lever 10 turns, and so that when the finger piece 14 is moved, the end 12 will be projected 55 outward through the perforation so as to permit the ready introduction of a globe or shade. The other arm 11 is a duplicate of the arm 10 having an end 16 projecting through the perforation 7, a bend 17 projecting through the slot 5 and a finger-piece 18 projecting through the slot 8, and the bend or knee 19 between the bend 17 and the finger-piece 18. By drawing the finger-pieces 14 and 18 together the wires or arms 60 are separated so as to permit the ready introduction of a shade or globe, that is, the fulcrums 15 and 19 bearing against the shell cause the bends 13 and 17 to move in the slots 4 and 5 and push the ends 12 and 70 16 outward so that the portions of the wires between the ends and the bends will be moved toward the shell as shown in Fig. 4, and when the finger-pieces are released they will separate so as to permit the arms 75 to spring into close relation with the shade and support the same at several points in the circumference.

I claim:

A shade or globe holder comprising a 80 shell formed on opposite sides with short slots with perforations between said short slots, and with long slots opposite the perforations, combined with shade-gripping arms having ends extending through said 85 perforations, bends extending through the short slots, finger-pieces extending through the long slots, said arms formed with knees between the bends at the sides and the finger-pieces.

In testimony whereof, I have signed this specification in the presence of two subscribing witnesses.

ARTHUR W. WELLINGTON.

Witnesses:

HENRY F. GRETZ,
A. C. REEGER.
